ATTORNEY.

UNITED STATES PATENT OFFICE.

SHERMAN J. DENTON, OF LA JUNTA, COLORADO.

SPRING COMPRESSOR.

Application filed June 4, 1928. Serial No. 282,805.

This invention relates to compression tools of the type used for the removal of valves in engines of motor-vehicles by releasing them of the pressure of their springs.

5 The invention pertains more particularly to tools of the above described character in which compression of the springs is effected by the moving together of two jaws at the ends of crossed levers, and its primary object 10 resides in the provision of a novel system of cooperative parts by which the movement of the levers is transmitted to the jaws. A further object of the invention resides in the provision of a novel and efficient element to 15 automatically lock the levers of the tool against retrograde motion as they are gradually brought together in the operation of compressing a spring between the jaws, and still further objects reside in details of construction as will fully appear in the course of 20 the following description.

The tool as hereinafter to be described and as shown in the accompanying drawings is further distinguished by a novel construction of its removable jaw and a novel and practical method of automatically locking the jaws in place. These features of the invention are, however, identical to those of the tool disclosed in my co-pending application 25 for patent, Serial No. 282,804 filed June 4, 1928, and they will but briefly be referred to in the description of the present tool.

In the drawings in which like characters of reference designate corresponding parts 30 throughout the views,

Figure 1 represents a sectional elevation of the improved tool;

Figure 2, a fragmentary plan view of one of the jaw-members of the tool in its operative relation to the respective lever-member of the same, looking in the direction of either of the arrows A in Figure 1;

Figure 3, a section taken on the line 3-3, Figure 1;

45 Figure 4, a section along the line 4-4, Figure 1;

Figure 5, a perspective view of one of the jaw-members and,

Figure 6, an elevation of the tool in its operative position with relation to the valve-spring of an internal combustion engine.

Referring further to the drawings, the tool comprises two crossed levers 5 and 6 pivoted together as at 7. The long arms 5^a and 6^a of the levers are preferably of channel section and they provide the handles by

which the tool is manually operated. The jaws of the tool, hereinafter to be more fully described are removably and reversibly fastened at the ends of shank-members 8 which are pivotally connected at one of their ends to the long arms of the levers by pins 9 and which are connected with the short arms of the levers by means of pivoted links 10. The shanks are lengthwise slotted at 12 to admit the links in the operative movement of the levers, and the pivotal connections of the links with the shanks are preferably established by means of lugs on strips 13 fastened to the shanks at opposite sides of their slots.

The links maintain the jaws in a substantially parallel position during their operative movement and they moreover increase the pressure exerted by the levers on the jaws in ratio to the decreasing distance between the levers when they are brought together in the operation of the tool.

The jaws, as best shown in Figure 5, consist of flanged plates 14 slotted at one end to admit the valve stem or other part in the operation of compressing a valve-spring, and provided at its opposite ends with opposed slide-ways to admit the free ends of the shank-members of the tool.

The body portion of each jaw is recessed as at 14^a and alined notches 14^b in opposite edges of the recess and in flanges 14^c that in conjunction with the body part of the jaw, constitute the slide ways hereinbefore referred to, provide means for the application of the locking means by which the jaws are locked in place on the shanks.

The locking means consist of dogs 15 pivoted on the shanks by short lugs 15^a in notches at the ends of the shanks, and having detents 15^b at right angles to their body portions that project through openings of the shanks to engage with the notches 14^b of the jaws at their sides lying against the outer surfaces of the shanks. A spring 16 on a headed stud 17 passing through an opening in the body portion of the dog and riveted in an aperture of the shank, yieldingly holds the dog in its normal locking position.

A lip 15^c on the dog curving outwardly through the before-mentioned longitudinal slot 12 of the shank provides a means for releasing the detents from the notches of the jaw, by finger-pressure.

The element by which the lever members are automatically locked together at differ-

ent distances apart, consists of a double rocker-arm 18 pivoted on one of the lever members as at 19, a lever 20 fulcrumed on the other lever of the tool at 21 and pivotally connected at the end of its long arm with the rocker arm 18 at 22, and a spring 23 connecting the short arm of the lever 20 with a fixed point of the lever 5 of the tool by means of a link 24, and lying in substantially parallel relation within the channel of the lever.

Two bars 25 pivotally connected at the free end of the rocker arm 18, have ratchet teeth 25^a engaging with a cross pin 26 on the lever 6, and the teeth of the two bars are staggered with relation to each other so that one or the other will lock the levers together at distances corresponding with fractions of the interdental spaces of the ratchet bars.

Springs 27 stretched between the ratchet bars and the lever-member 6 hold the bars in contact with the pin. Triggers 28 pivoted on the lever 6 at 29, have finger-humps 28^a projecting through a slot of the lever member, to be brought in engagement with the locking bars for the purpose of releasing their teeth from the pin when it is desired to restore the parts of the tool to their normal position in which both the jaws and the levers are spread apart.

The locking bars are guided in their movement by a yoke 30 which also provides a stop that prevents the long arms of the levers from meeting when they are closed together in the operation of the tool, thereby eliminating the danger of injury to the hands of the user. The yoke is extended inside the lever to which it is attached, to provide a more firm support for the cross-pin engaged by the ratchet bars and the pivot pin of the triggers.

It will be apparent that in the operation of the tool, the pressure exerted by the jaws upon an interposed spring constantly increases as the jaws approach each other by reason of the connections between the levers and the shanks upon which the jaws are carried.

There is little or no strain on the ratchet bars inasmuch as their angle to the levers constantly decreases while the levers are brought together as may be seen in Figure 6.

The jaws are easily applied to the shank-members by the automatic locking means which are independent from other parts of the tool; and they are readily removed by pressure upon the lips of the dogs that lock them in place. The jaws are interchangeable and reversible and jaws of different sizes may be supplied to accommodate valve-constructions of varying forms and proportions.

The ratchet-lock for the levers is easily released by pressure upon the triggers and

it is to be observed that all the parts of the lock are between and within the channelled arms of the levers.

Figure 6 illustrates the method of using the tool. The jaws are inserted at opposite ends of a valve-spring 32 or any portion thereof and straddle the valve stem 33. When the handle-parts of the levers are brought together the jaws are moved together and compress the spring with increased force. The compression of the spring moves its end away from the cross pin 34 on the valve-stem upon which it normally bears and the pin may thus be withdrawn from the valve stem for the removal of the valve for renewal or repair.

Having thus described my invention what I claim and desire to secure by Letters-Patent is:

1. A tool of the character described comprising crossed levers having long and short arms at opposite sides of their fulcrum, jaw-carrying members pivoted at one end on the long arms of the levers, and pivoted links connecting the short arms of the levers with the jaw-carrying members and extending from the short arms rearwardly in the general direction of the long arms.

2. In a tool of the character described, crossed levers, and a locking element to secure the levers at a given distance apart, comprising a rocker arm and a pin on one of the levers, a bar pivoted on the rocker arm and having ratchet teeth engaging with the pin, a lever fulcrumed on the other lever in connection with the rocker arm, and a spring acting upon the lever of the rocker arm.

3. In a tool of the character described, crossed levers and a locking element to secure the levers at a given distance apart, comprising a rocker arm and a pin on one of the levers, a bar pivoted on the rocker arm and having ratchet teeth engaging with the pin, a spring to yieldingly maintain said engagement, a lever fulcrumed on the other lever in connection with the rocker-arm, and a spring acting upon the lever of the rocker arm.

4. In a tool of the character described, crossed levers, and a locking element to secure the levers at a given distance apart, comprising a rocker arm and a pin on one of the levers, a bar pivoted on the rocker arm and having ratchet teeth engaging with the pin, a lever fulcrumed on the other lever in connection with the rocker-arm, a spring acting upon the lever of the rocker arm, and a pivoted trigger to disengage the bar from the pin.

5. In a tool of the character described, crossed levers one of which has a slot, and a locking element to secure the levers at a given distance apart, comprising a rocker arm and a pin on one of the levers, a bar

pivoted on the rocker arm and having ratchet teeth engaging with the pin, a lever fulcrumed on the other lever in connection with the rocker-arm, a spring acting upon 5 the lever of the rocker arm, and a trigger extending through said slot and adapted to disengage the bar from the pin.

6. In a tool of the character described, crossed levers, and a locking element to 10 secure the levers at a given distance apart, comprising a pin on one of the levers, and a locking bar in movable connection with the other lever, the bar extending away from the fulcrum of the levers in the space 15 between corresponding arms thereof, and having ratchet teeth whose shoulders face the fulcrum to engage the pin.

7. In a tool of the character described, crossed levers, and a locking element to 20 secure the levers at a given distance apart, comprising a rocker arm and a pin on one of the levers, bars pivoted on the rocker arm to move separately about a common axis, the bars having ratchet teeth staggered with 25 relation to each other to successively engage the pin, a lever fulcrumed on the other lever, in connection with the rocker-arm, and a spring acting upon the lever of the rocker arm.

8. In a tool of the character described, 30 crossed levers having short arms and long arms at opposite sides of their fulcrum, and a locking element to secure the levers at a given distance apart, comprising a ratchet bar in movable connection with the long arm 35 of one of the levers, a pin on the same arm, engaged by the ratchet bar, and a yoke guiding the ratchet bar in its movement and projecting in the space between the long arms of the levers to limit the extent to 40 which they may be closed together.

9. In a tool of the character described, crossed levers having short arms and long arms at opposite sides of their fulcrum, and a locking element to secure the levers at a 45 given distance apart, comprising a rocker arm and a pin on the long arm of one of the levers, a toothed bar connected with the rocker arm and engaging with the pin, a lever fulcrumed on the long arm of the 50 other lever in connection with the rocker-arm, and a spring connecting the toothed bar with a fixed point of the lever arm carrying the pin, and extending lengthwise with relation to said arm. 55

In testimony whereof I have affixed my signature.

SHERMAN J. DENTON.
